UNITED STATES PATENT OFFICE.

CHARLES A. SCHILD, OF FORT WAYNE, INDIANA, ASSIGNOR TO GENERAL ELECTRIC COMPANY, A CORPORATION OF NEW YORK.

ELECTRICAL CONNECTER.

Application filed October 30, 1923. Serial No. 671,740.

The present invention relates to detachable connectors whereby a circuit wire may be operatively connected to electric devices such as motor brush holders, spark plugs, etc.

5 The object of my invention is to provide an improved connector which may be connected and disconnected from electric devices by the unskilled without the use of tools, and without danger of becoming injured by handling, which when in applied 10 position will insure a highly efficient contact under all operating conditions and without fatiguing under vibrations, and which may be economically manufactured.

15 One form of the invention is illustrated in the accompanying drawing in which Fig. 1 is a side elevation with part in section of a well known type of electric motor with my connector applied to the brush holder there- 20 of; Fig. 2 is an enlarged perspective view of a detached brush holder and connector attached; Fig. 3 is a similar perspective with the connector detached, and Figs. 4 and 5 are detail views showing the construction of 25 the connector.

In the construction shown in the drawing, the commutator brush 1 is in the form of a prismatic block of gas carbon bearing 30 at one end against the motor commutator 2 and freely movable lengthwise in a metal sleeve or brush holder 3 which is threaded at its outer end for an adjusting screw 4 for varying the pressure on the brush through 35 its spring 5 also mounted with the brush holder.

The brush holder is insulatively mounted 40 in the motor frame 6 by a cylindrical shell 7 of fiber into which it is longitudinally forced and then driven together into a suitable hole in the motor frame opposite the commutator.

The inner end of the brush holder 3 extends beyond the end of the insulating shell and is provided with retaining shoulders or 45 a peripheral groove 8 for the reception of the connector clip 9 at the end of the lead wire 10.

The connector clip 9 consists of a spring

ring or loop of helically wound stiff wire, preferably phosphor bronze. The size of the ring or loop is such that upon being forced like a garter over the end of the brush holder 3, it will recoil sufficiently to firmly engage the walls of the groove 8 and be at the same time readily yieldable to 50 permit sidewise movement of the lead wire 10 to which it is joined.

The joint between the connector clip 9 and the feed wire 10 is shown enlarged in Fig. 4 and is made by stripping the braided insulation 11 off the end portion of the wire which is then threaded through two or three convolutions 12 at each end of the helical coil and then closely wrapped over the end of the braided insulation 11 to prevent it 55 from fraying or receding. A drop of solder 13 applied over the joint serves to hold all parts in fixed electrical and mechanical relation.

While I have shown and described the best 60 embodiment of the invention known to me, I do not desire to be restricted thereto.

What I claim as new and desire to secure by Letters Patent of the United States, 65 is:—

1. A connector clip consisting of a spring 70 wire helix bent into ring shape and an insulated conductor wire having a bared end threaded through convolutions at both ends of said helix and secured about the insulation of said wire.

2. An electrical connector consisting of a 75 spring wire helix bent into ring shape and a conductor wire threaded through the ends of said helix and soldered thereto.

3. An electrical connector consisting of a 80 spring wire helix bent into ring shape and a conductor wire with braided insulation having one end bared of insulation and threaded through the end convolutions of 85 said helix and wrapped about the end of the braided insulation to bind it in place.

In witness whereof, I have hereunto set 90 my hand this 24th day of October, 1923.

CHARLES A. SCHILD.
